UNITED STATES PATENT OFFICE.

JOHN W. BERWICK, OF BROOKLYN, NEW YORK.

ENVELOP FOR PHOTOGRAPHIC FILMS OR PLATES.

1,044,123.

Specification of Letters Patent. Patented Nov. 12, 1912.

Application filed June 17, 1911. Serial No. 633,794.

To all whom it may concern:

Be it known that I, JOHN W. BERWICK, a citizen of the Dominion of Canada, and resident of Brooklyn, in the county of Kings 5 and State of New York, have invented certain new and useful Improvements in Envelops for Photographic Films or Plates, of which the following is a specification.

This invention relates to an envelop to be 10 used in the developing of photographic films, and it constitutes an improvement on the invention described in my Patent #1,032,648, patented July 16, 1912. The invention described in said co-pending application is embodied in an envelop to 15 which there is detachably secured, an instruction sheet upon which memoranda are made relating to the contents of the envelop, and a portion of this instruction sheet is 20 detachable to form the customer's coupon or check, identifying the envelop and its contents, and forming a receipt to be kept by the customer until delivery is made.

The envelop is particularly useful to hold 25 films left to be developed. It frequently happens that such films are left at a branch office from which the film must be forwarded to the place where it is to be developed.

The object of this invention is to provide 30 means in connection with the aforesaid envelop to enable a duplicate record to be conveniently made of the instruction sheet of an envelop of the class described, so that one of the instruction sheets may be kept 35 at the branch office where the film is left, and the other instruction sheet may be sent forward with the envelop when the film goes to be developed.

A further object of the invention is to 40 provide the envelop with a larger and more serviceable customer's check, than was formerly possible.

In carrying out my invention I provide 45 an original instruction sheet which preferably lies over the upper portion of the envelop, and I also provide a duplicate sheet overlying the original sheet and detachably secured to the edge thereof. The original instruction sheet and the duplicate have 50 similar blanks which are superposed or in corresponding register, to receive remarks or instructions; and at the edges where they connect together, they are similarly formed with similarly registering coupons some of 55 which are detachable; these coupons facil-

tate the work to be done and expedite the handling of the envelops.

In the accompanying drawings which fully illustrate my invention, Figure 1 is a front elevation of this envelop. Fig. 2 is a 60 vertical section through the envelop taken in a front and rear direction and particularly illustrating the manner in which the original and duplicate instruction sheets are secured to the envelop. Fig. 3 is a view 65 similar to Fig. 2, but with the duplicate instruction sheet removed. Fig. 4 is a front elevation of the duplicate instruction sheet detached from the envelop and retained as a memorandum at the branch office or receiving point, and also constituting a record 70 of the transaction after the developed films have been delivered. Fig. 5 is a front elevation of the customer's coupon which forms the lower half of the duplicate instruction sheet. 75

Referring more particularly to the parts, 1 represents the body of the envelop which is of rectangular form, with a transverse slit 2 in the forward wall thereof, and having a folding and sealing flap 3 at the upper edge of the envelop, as shown. I provide an original instruction sheet 4 which extends into the lower portion or pocket 5 of the envelop, through the said slit 2, the 80 upper portion of this instruction sheet lying against the forward and upper wall of the envelop. To the upper edge of this original instruction sheet is attached a duplicate instruction sheet 6. This sheet is detachably secured on the line 7. The lower portion of the duplicate instruction sheet is 85 formed into a customer's coupon or check 8 which is detachable from the body of the original sheet on the score line 9 which extends horizontally across the duplicate instruction sheet about opposite the slit 2. The upper edges of the two instruction sheets are formed with detachable coupons 90 10 which correspond in position to each other, that is, the corresponding coupons 100 are superposed and have similar printed instructions relating to the films within the envelop.

When a film is left to be developed, the 105 clerk receiving the film places a carbon sheet or transfer sheet in the space 11 between the duplicate and original instruction sheets, and when the name and address 110 blanks and other blanks are filled in, the

instructions, remarks, etc., will have all been made in duplicate. When this has been done, the duplicate instruction sheet is detached on the line 7. Certain of the detachable coupons 10 may then be detached from the original sheet leaving others which describe what is to be done in connection with the film or negative within the envelop, and corresponding coupons on the duplicate 5 instruction sheet are marked or removed, so that the duplicate instruction sheet is an exact copy of the original. The film is then placed within the envelop and pinned or sealed therein by means of the flap 3, and 10 is then forwarded to the place where the film is to be developed. The duplicate instruction sheet then remains in the branch office and gives a complete record of the 15 transaction. After the customer's coupon 20 8 is removed, this duplicate instruction sheet forms a coupon or card to be kept at the branch office as indicated in Fig. 4. The coupons 10 on the upper edge of the instruction sheet facilitate the handling of 25 the card, and expedite placing and removing it from its proper drawer.

The envelop, the customer's coupon, and the original and duplicate instruction sheet are correspondingly marked or provided 30 with a number such as No. 3001, as indicated.

The original sheet 4 is preferably detachably secured by paste or glue at points 12 of the envelop; before the envelop is returned to the branch office, this instruction 35 sheet is detached, and constitutes a record at the developing office. The returned envelop is used to hold the negatives or prints delivered to the customer, and the envelop, 40 if desired, may be conveniently folded at the slit 2. By providing such a duplicate instruction sheet, left at the branch office, that is, the receiving office, in case the customer calls at any time to inquire for the 45 film before it has been returned, the branch

office can immediately communicate with the developing main office or place, and can give complete data of the order through this duplicate sheet, as to when the order was taken, etc.; and, to do this, it is merely 50 necessary for the clerk at the branch office to note the number of the customer's check; and no delay is occasioned to the customer.

What I claim and desire to secure by Letters Patent is:—

1. An envelop of the class described, having a body with a slit in the forward wall thereof, an original instruction sheet passing into the interior of said envelop through said slit and received in the lower portion 60 of said envelop, the upper portion of said instruction sheet lying over the upper portion of said envelop, and a duplicate instruction sheet detachably secured to said original instruction sheet and superposed 65 thereupon, said duplicate instruction sheet having a detachable extension below said slip forming a customer's coupon and lying wholly outside of said envelop.

2. An envelop of the class described, having a body with a slit in the forward wall thereof, an original instruction sheet passing into the interior of said envelop through said slit and received in the lower portion 70 of said envelop, the upper portion of said instruction sheet lying over the upper portion of said envelop, and a duplicate instruction sheet detachably secured to said original instruction sheet and superposed 75 thereupon, and a customer's check detachable from the lower edge of said duplicate instruction sheet, and lying wholly outside of said envelop.

Signed at New York city in the county of New York and State of New York this 85 16th day of June A. D. 1911.

JOHN W. BERWICK.
